JUVENILE AUTO

Charles E. Steele, Olney, Ill., assignor to American Ma-
chine & Foundry Company, a corporation of New
Jersey

Filed June 5, 1969, Ser. No. 17,529

Term of patent 14 years

Int. Cl. D21—02

U.S. Cl. D34—15

FIG. 4

FIG. 5

FIG. 6

FIG. 1 is a perspective view of a juvenile auto of my novel design;

FIG. 2 is a top plan view thereof;

FIG. 3 is a side elevation view thereof;

FIG. 4 is a rear view thereof;

FIG. 5 is a front view thereof; and

FIG. 6 is a perspective view of another embodiment of the FIG. 1 vehicle, wherein the windshield has been eliminated and a steering wheel has been substituted for the steering handles.

I claim:

The ornamental design for a juvenile auto, substantially as shown.
